UNITED STATES PATENT OFFICE.

ANTHONY E. MONGELUZZO, OF BARNESBORO, PENNSYLVANIA.

SHOE FASTENER.

Application filed April 27, 1923. Serial No. 634,928.

To all whom it may concern:

Be it known that ANTHONY E. MONGELUZZO, a citizen of the United States, residing at Barnesboro, in the county of Cambria and State of Pennsylvania, has invented certain new and useful Improvements in Shoe Fasteners, of which the following is a specification.

In carrying out the present invention it is my purpose to provide a shoe fastener which is adapted to be employed in conjunction with the usual lacing fastener of shoes for permitting the shoe to be readily taken off or put on without the necessity of unlacing the shoe which is very tedious.

The primary object of the invention resides in the provision of such a fastener that is comparatively simple of construction and one that may be incorporated with shoes without material increase of cost of production thereof.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views, and wherein:

Figure 1 is a perspective of a shoe equipped with my improved fastener;

Figure 2 is an enlarged fragmentary elevation of the shoe more clearly disclosing my improved fastener, and

Figure 3 is a cross section taken upon the line 3—3 of Figure 2 and looking downwardly in the direction of the arrows.

With particular reference to the drawings there is shown a shoe 5 of conventional form wherein the upper 6 is open at its front side, the opposite edges of this opening being provided with eyes for receiving the usual lace 7.

My invention includes an opening 8 in the shoe upper at one side of the usual opening and of a length equivalent to this opening. Upon opposite edges of said opening 8 are spaced pairs of metal plates 9 secured to the shoe upper in any manner desirable.

The inner ends of these pairs of plates 9 extend within said opening 8 and are of curvilinear form as at 10, it being, of course, understood that the plates 9 of each pair are curved in opposite directions for forming an open ended pocket therebetween. 55

Between each pair of plates at opposite edges of the opening 8 is a cross bar 11, the opposite ends thereof being formed with rounded heads 12 that are adapted for movement through the pockets formed by the plates 9 of each pair. Upon each of the cross bars 11 and inwardly of the heads 12 are pendant links 13, the lower ends of the same being in turn engaged over the next lower bar as more clearly brought out in Figure 2.

The uppermost bar 11 is provided with an operating handle 14 whereby the bars 11 may be drawn upwardly or extended downwardly in unison for disengaging the heads 12 from the pockets formed by the pairs of plates 9 for thereby opening the upper and 75 permitting the shoe to be put on or taken off.

In actual practice it is necessary that the lace 7 be properly adjusted and for accomplishing this purpose the bars 11 are first 80 positioned between the pairs of plates 9 and the lace 7 unlaced from the shoe. After this has been accomplished the shoe may be placed upon the foot and laced to the desired tightness, it being understood that after this lace 85 has been applied the shoe may be taken off and put on without again lacing or unlacing the shoe.

Although I have herein shown and described the preferred embodiment of the 90 present invention, it is nevertheless to be understood that minor changes may be made therein, without departing from the spirit and scope of the invention as claimed.

Having thus described my invention, what I claim as new and desire to secure by Letters Patent is:

A quick detachable shoe fastener including a plurality of pairs of plates secured to the opposite edges of the opening in the shoe 100 upper in spaced relation, the plates at one side of the opening being in opposite corresponding relation with the plates at the other side of the opening, all of said plates

being formed with sockets beyond the edges of the upper, a plurality of fasteners having the ends formed for cooperation with corresponding sockets on the opposite edges of the upper, and means securing the fastening elements in equal spaced relation with the plates and positioned between opposite

plates in fastened relation adapted for moving all of said fastening elements into or out of fastening cooperation with said plates 10 simultaneously.

In testimony whereof I affix my signature.

ANTHONY E. MONGELLUZZO.
